Des. 204,103
Patented Mar. 15, 1966

204,103

BOTTLE CLOSURE

Frank L. Lydon, Cypress, Calif., assignor to Sun Battery
Company, Santa Ana, Calif., a California corporation

Filed Apr. 30, 1965, Ser. No. 85,047

Term of patent 14 years

(Cl. D58—26)

I claim:

The ornamental design for a bottle closure, substantially as shown.
